VACUUM CLEANING IMPLEMENT

Elza W. Powell, Indianapolis, Ind.

Original application December 31, 1935, Serial No. 57,025. Divided and this application November 10, 1936, Serial No. 110,172

1 Claim. (Cl. 15—156)

This invention relates to vacuum cleaning devices and particularly to a vacuum cleaning head.

The general object of the invention is to provide an implement of this character including a handle and a vacuum cleaning head, the head being mounted upon the handle for oscillation in a plane parallel to the plane of the handle through an arc of a circle and the head and handle being provided with means whereby the head may be held in any adjusted position.

Another object is to provide a device of this character which is particularly adapted for use in a variety of situations because of the fact that the head is oscillatable upon the handle, thus permitting the handle to be disposed either in the same plane as the head or in any desired angular relation thereto, so that the implement may be used beneath low articles of furniture, on walls, ceilings or in places which are otherwise hard to get at with the ordinary vacuum head.

A further object is to provide a device of this character in which the connection between the handle and the head is very simple and yet airtight.

This application is a division of my application for patent on Vacuum cleaning systems, filed on December 31, 1935, Ser. No. 57,025.

My invention is illustrated in the accompanying drawing wherein:

Figure 1 is a diagrammatic sectional view showing one manner in which my vacuum cleaning implement may be connected up in a vacuum cleaning system.

Figure 2 is a top plan view of the cleaning head and a portion of the handle.

Figure 3 is a section on the line 3—3 of Figure 2.

Figure 4 is a like view to Figure 3 but showing the handle as disposed at an inclination to a horizontal plane or at an angle of approximately 130° to the plane of the mouth of the head.

Figure 5 is a like view to Figure 4 but showing the handle disposed at an angle of 180° to the mouth.

Figure 6 is a fragmentary section on the line 6—6 of Figure 5.

Referring to the drawing, it will be seen that the vacuum head itself designated 10 is elongated and is somewhat elliptical in plan view. This head is formed with an arcuate slot 11 on its rear face. On its underface, the head has the downwardly and slightly inwardly extending walls 12 defining between them the mouth 13. These

walls 12 at their lower ends are slightly flanged outwardly.

Oscillatably disposed within the slot 11 is the tubular handle 14 which extends through this slot and at its inner end is formed with a transversely arcuate but longitudinally elongated flange 15 which fits snugly against the transverse arcuate or concave inner face of the head 10.

Attached to the inner face of the head 10 on each side of the slot 11, as shown in Figure 6, are the arcuate or semi-cylindrical collars 16. These collars 16 are each outwardly expanded at its outer end and these outwardly expanded portions 17 are welded or otherwise attached to the inner face of the head so that the body of each collar 16 inward of the portion 17 is spaced from the wall of the head 10 to receive the lateral marginal portions of the flange 15. For the purpose of holding the collars 16 in snug engagement with this flange 15, I provide the binding screws 18 which extend through the wall of the head 10, as shown in Figure 6, and are either attached to the collars 16 or are provided as shown, with heads 19 bearing against the inner faces of the collars. The screws 18 extend through the wall of the head 10 just outward of the ends of the flange 15 and are provided on the exterior of the head with the nuts 20.

The construction which I have described permits the handle 14 to be turned to any desired angle to a plane extending through the head at right angles to the mouth 13 thereof or into a position where the handle is disposed within this plane, as shown in Figure 5. The handle is, therefore, shiftable into any desired angular position with the head so that the head may be used, as shown in Figure 1, with the handle so disposed that the head and handle may be forced beneath very low articles of furniture or the head may be disposed at the other extreme, as shown in Figure 5. Thus the head is adapted to be used for cleaning ceilings, walls, floors, and because of the adjustability of the handle, may be used wherever the ordinary vacuum head is difficult to manipulate.

Furthermore, it is to be particularly noted that the head 10 and the handle 14 are held rigidly in their adjusted positions by means of the nuts 20 and screws 18, so that the head cannot oscillate upon the flange 15 and get out of the correct adjusted position.

While I have not illustrated a detailed construction whereby the plate 15 may be inserted within the head 10, yet it will be obvious that the

head 10 may readily be constructed in two sections inserted over the ends of the plate 15 and afterwards welded, brazed or otherwise connected to each other. A line indicating the joint between the two sections and this welding is designated 21 in Fig. 2. However, it is to be understood that this is purely illustrative and the head 10 might be formed in two longitudinal sections welded to each other or with a section initially 10 separate from the body of the head 10 which will permit the insertion of the plate 15, and then this other section might be welded or otherwise attached to the head.

It will be seen that I have provided a construction which does away with the necessity of packing rings, stuffing boxes or the like, and thus may be very cheaply made. Of course, as is obvious, the head itself might be differently formed for different purposes as are the heads 20 of the usual vacuum cleaners, without departing from the spirit of my invention as defined in the appended claim.

What is claimed is:—

A vacuum cleaning implement, including a longitudinally elongated hollow head having a transversely curved outer wall, the wall being arcuately slotted, a tubular handle extending into said slot and having a laterally extending flange at right angles to the handle, extending in opposite directions and which is transversely curved to fit snugly against the inner face of the head, laterally disposed transversely arcuate collars attached to the inner face of the head on each side of the slot, each collar having a body portion spaced adjacent the slot from the inner face of the head to receive between it and the said face of the head an end portion of the handle flange, binding screws engaged with the body portions of the collars and extending across the adjacent end edges of the flange, said screws passing through the head, and binding nuts disposed upon the exterior ends of said screws, said nuts when threaded up on the screws compressing the collars against the handle flange to secure the handle in a fixed position relative to the head. 5 10 15 20
